US0D1065553S

(12) **United States Design Patent** (10) **Patent No.:** **US D1,065,553 S**
(45) **Date of Patent:** **** Mar. 4, 2025**

(54) **LUMBAR SUPPORT**

(71) Applicant: **Nadan Xie**, Jieyang (CN)

(72) Inventor: **Nadan Xie**, Jieyang (CN)

(**) Term: **15 Years**

(21) Appl. No.: **29/899,419**

(22) Filed: **Aug. 9, 2023**

(30) **Foreign Application Priority Data**

Feb. 24, 2023 (CN) 202330073451.8

(51) **LOC (15) Cl.** **24-02**
